UNITED STATES PATENT OFFICE.

ALBERT A. SCHWARTZ, OF NEW YORK, N. Y., ASSIGNOR TO ROYAL TYPEWRITER COMPANY, INC., OF NEW YORK, N. Y., A CORPORATION OF NEW YORK.

PAPER-FEED ROLL FOR WRITING-MACHINES.

1,247,456.

Specification of Letters Patent. Patented Nov. 20, 1917.

Application filed April 28, 1917. Serial No. 165,057.

To all whom it may concern:

Be it known that I, ALBERT A. SCHWARTZ, a citizen of the United States, and a resident of the borough of Bronx, in the city of New York, county of Bronx, and State of New York, have invented certain new and useful Improvements in Paper-Feed Rolls for Writing-Machines, of which the following is a specification.

10 The present invention relates generally to type-writing machines and has more particularly reference to a pressure roll or a system of pressure rolls coöperating with the platen to effect the proper feed of the 15 paper and to the means for varying the tension of said pressure roll or pressure roll system against the platen.

In the character of machine under consideration there is usually employed what is 20 known as a front pressure roll and a rear pressure roll, both of which are located below the axis of rotation of the platen. These pressure rolls are held in yielding engagement with the platen and suitable means are 25 provided for effecting the release of said rolls at the will of the operator.

In the art as heretofore practised, it has been the usual custom to employ flat springs 30 for urging the rolls into engagement with the platen, and such flat springs have been located at what seemed the most convenient point for creating the right tension upon the pressure rolls, with the result that at 35 times these springs have been located at points where they were not readily accessible for the purpose of replacement or adjustment, and, furthermore, where they might easily become deranged or displaced by the moving parts of the machine. Also the character of the springs used and their location 40 both contributed to rendering it extremely difficult or inconvenient to vary the tension of the springs or the pressure with which the rolls engage the platen.

45 The main object of this invention is to so relate the springs which urge the pressure rolls, and especially the front pressure roll, to the other parts of the machine that access for adjustment or repair may easily and 50 quickly be made. Another object of the invention is to make the utilization possible of a spring commonly known as a coiled spring in place of flat springs.

With these and other objects in view, one 55 feature of the invention consists in so ar-

ranging the spring means for the front pressure roll that its tension may be adjusted from the rear of the carriage. In the character of front pressure roll commonly used in machines of this type, there is utilized as 60 a part of the supporting means for the front pressure roll a lever which is pivotally supported on the carriage. With this construction the spring means will preferably be arranged to press against said lever at a 65 point in rear of and below its pivotal support, and the end of the spring is housed in the lower carriage rail and may be adjusted from the rear thereof.

A further feature of the invention resides 70 in rendering both the front and rear pressure roll springs accessible and adjustable from the rear of the carriage.

So far as the feature relating to the use of the coiled spring is concerned, the invention 75 embraces a pressure roll mounted on suitable supporting means on the carriage, together with two bearings, both of which are provided with means for preventing lateral displacement of the coiled spring, while permitting its central portion to remain unguided and capable of flexure out of its own plane. One of said bearings is adjustable to vary the tension of the opening, and, preferably, the adjustable bearing is the one 80 85 which is mounted on the carriage.

In the accompanying drawings the invention is illustrated in several preferred forms, and in these drawings:

Figure 1 is a plan view of the lower portion of the carriage, and the elements associated therewith, the platen and the rear pressure roll and the paper pan being removed, and parts being broken away and shown in section for the sake of clearness in 90 95 illustration.

Fig. 2 is a vertical sectional view on the irregular line 2—2 both through the front and rear pressure rolls, and with the platen indicated diagrammatically.

Fig. 3 is a view similar to Fig. 2 showing a modified form of the invention.

Fig. 4 is a detail sectional view on the line 4—4 of Fig. 3.

5 is the platen suitably mounted on the carriage in any desired manner, and 6 indicates the lower carriage rail of the carriage. 7 is the support for the paper pan 8. 9 is the front pressure roll and 10 is the rear pressure roll. The front pressure roll is 110

mounted in the carriage by a suitable supporting means which, in this instance, takes the following form. 11 indicates a lever having a forwardly extending arm 12 and a rearwardly extending arm 13, said lever being pivoted at its central portion on the rod 14. There will, of course, be as many of these levers as may be necessary to properly support the front pressure roll, but only one need be described since they are all constructed alike. Mounted at a point below the pivotal center 14 of the lever 11 and in the rear thereof, is a stem or projection 15 which extends rearwardly and is opposite to an aperture 16 in the rear wall of the lower carriage rail. Surrounding said stem 15 and seated within this aperture which forms a housing therefor is a coiled spring 17. Seated in the aperture 16 and accessible from the rear of the lower carriage rail is a set screw 18. It will be observed that the stem 15, the aperture 16 and set screw 18, form bearings for the said coiled spring 17, and that the tension of this spring may be varied by adjusting the screw 18. Suitable means are provided for releasing the pressure roll 9 in this instance taking the form of a releasing cam bar 19 which is suitably mounted in the lower carriage rail 6 at a point above the housing for the springs 17 and the screw 18. The said cam releasing bar 19 is provided with a suitable cam surface as 20 which engages with the rearwardly extending arm 13 of the lever 11 and is operated in a manner well understood in the art to effect the release of the front pressure roll. Suitable means are provided for holding the rod 14 and cam bar 19 in place consisting here of the retaining members 36 which overlie both of said members and which are attached to the carriage as by means of the screws 37.

The rear pressure roll 10 is mounted in the swinging lever 21 which is pivoted at 22 on the paper pan support 7, and, in the form here disclosed, the cam releasing bar 19 may be provided with another cam surface 23 which acts against the lever 21 and thus causes the rear pressure roll 10 to be moved out of contact with the platen. Normally, however, this rear pressure roll will be held in yielding contact with the platen by means of the coiled spring 24 which is seated between the two bearings 25 and 26, said bearings being constructed to prevent lateral displacement of the spring 24, while leaving its central portion unguided. In the present form the bearing 25 consists of an extension, as shown, mounted on the paper pan support, while the bearing 26 consists of a screw adjustably mounted in the lug 27 of the lever 21 and having also a reduced portion 28 at the point where the spring 24 comes in engagement therewith. The coiled spring 24 here surrounds the reduced por-

tions or stems of both bearings 25 and 26 and is thus kept from displacement. The tension of the spring may be varied by adjusting the screw 26 in the lug 27.

The construction shown in Figs. 1 and 2, 70 therefore, renders it possible to adjust both the springs for the front and the rear pressure rolls from the rear of the carriage and places the springs in a position where they are not liable to become displaced by the 75 moving parts of the mechanism.

In the modification shown in Fig. 3 the arm 12 of the front pressure roll is provided with a bearing having the stem or reduced portion 29, and the lower carriage 80 rail is also provided with a bearing having a reduced portion or extension 30. Between these two bearings there is a coiled spring 31 which is thus held securely in position by the projecting stems 29 and 30, while leaving its central portion unguided. In this instance it will be noted that the bearings for the spring are on the front of the mechanism. This construction is not so advantageous as where the parts are accessible 90 from the rear of the lower carriage rail but it serves to illustrate another form of advantageous means for utilizing a coiled spring for the purpose of holding a pressure roll under tension against the platen. In 95 this instance the reduced portion 30 is carried by a plate 32 having the oblong slot 33 and attached to the lower carriage rail by means of the set screw 34. It will be obvious that by loosening the screw 34 the 100 plate 32 may be adjusted up or down, as the case may be, to obtain the requisite tension of the spring 31, after which the set screw will be tightened and the parts remain in the position to which they have 105 been adjusted.

In Fig. 3 the rear pressure roll 10 is conventionally illustrated as being held in engagement with the platen by means of the flat spring 35 engaging the lever 21. 110

An important feature of the means devised for utilizing the coiled spring resides in the fact that while the ends of the coiled spring are securely held by reduced portions of the bearings or by suitable housing, yet the middle portion of the spring is left unguided and therefore acts as a sort of flexible joint during the pivotal movement of the lever carrying the pressure roll. 115

I claim:

1. A laterally movable carriage including a lower carriage rail, a platen and a front pressure roll for the platen, both mounted on said carriage, means for supporting the pressure roll including a lever, having a 125 forwardly and a rearwardly extending arm, pivoted at its central portion, the pressure roll being mounted on the forwardly extending arm, a releasing cam bar supported in the lower carriage rail and engaging the 130

- rearwardly extending arm, a coiled spring pressing against the supporting means in the rear of and below the pivotal point of the lever, said spring being housed in the 5 lower carriage rail below the releasing cam bar, and means accessible from the rear of the lower carriage rail for adjusting the tension of the spring.
2. A laterally movable carriage including 10 a lower carriage rail, a platen and a front pressure roll for the platen, both mounted on said carriage, means for supporting the pressure roll including a pivoted lever, a rearwardly extending stem on said lever below the point of its pivotal support, a coiled spring surrounding said stem and housed in the lower carriage rail, means accessible 15 from the rear of the lower carriage rail for adjusting the tension of the spring, and 20 means for actuating the lever to release the pressure roll.

3. A laterally movable carriage including

a lower carriage rail, a platen and a front pressure roll for the platen, both mounted on said carriage, means for supporting the 25 pressure roll including a lever, having a forwardly and a rearwardly extending arm, pivoted at its central portion, the pressure roll being mounted in the forwardly extending arm, a releasing cam bar located in 30 the lower carriage rail and engaging the rearwardly extending arm, a rearwardly extending stem on the lever below its pivotal point, a coiled spring surrounding said stem and housed within the lower carriage 35 rail below the releasing cam bar, and means accessible from the rear of the lower carriage rail for adjusting the tension of the spring.

Signed at New York city, in the county 40 of New York and State of New York, this 26th day of April, 1917.

ALBERT A. SCHWARTZ.
